FLASHLIGHT

Rodger F. Becker, Kalamazoo, Mich.

Application February 23, 1946, Serial No. 649,686

1 Claim. (Cl. 240—10.6)

1

This invention relates to a flashlight and particularly to one having an elongated flexible cable supporting the bulb at a distance from, and in adjustable relationship to, a battery carrying case.

While there have been many types of lights hitherto used for illuminating machinery during maintenance or repair work thereon, there has remained unfilled a need for a small, readily portable source of light which could illuminate the places difficult to reach with ordinary illuminating means, such as the deeper recesses of an automobile engine. This source of illumination should be small in order that it may be placed in a wide number of otherwise difficult places, sturdy in order to stand hard usage, and economical to make. It should supply its own supporting means, the direction of the beam should be adjustable with respect to the remainder of the instrument and, when the adjustment has been made it should be able to support itself in such adjusted direction.

Accordingly, in developing my invention a major object has been to provide a readily portable and completely self-contained source of illumination, having sufficiently small overall dimensions to enable it to reach and readily illuminate the deep, and usually dark, recesses of machinery such as an automobile engine, which cannot be readily illuminated by present conventional means.

A further object has been to provide such an instrument wherein the bulb is supported at a distance from, and in adjustable relationship to, a battery carrying case.

A further object of my invention has been to provide an instrument as aforesaid which will support itself in a variety of positions without the necessity of additional or special attachments, such as rings, hooks and the like.

A further object of my invention is to provide such an instrument constructed with a maximum of simplicity by which to minimize both cost and maintenance problems.

Other objects and purposes of my invention will be apparent to those acquainted with equipment of this sort and the problems which it is intended to solve, upon reference to the accompanying drawing and the following specification.

In the drawing, the figure represents a partially broken side view of my flashlight wherein the sectioned parts are taken in central longitudinal section.

In providing a flashlight meeting the objects and purposes above outlined, I provide a cylindrical battery carrying case, a flexible cable

mounted thereon of such type that it will stay in whatever position it is placed within its constructional limits, and which cable supports at its end a flashlight bulb holder. When suitably fitted with batteries and a flashlight bulb, the instrument may be utilized for projecting light into a wide variety of places otherwise inaccessible to illumination by having the cable of such stiffness that it will remain in any ordinary position in which it is placed so that no further support will be needed for the flashlight bulb. Further, the cable itself may be bent into the form of a hook and the entire instrument placed over a convenient support with the illuminating head directed as desired and the whole thus adequately supported without the need for further supporting means.

Referring now to the drawing there is provided a cylindrical battery case 1 receiving therein batteries 2 and 3 of the ordinary dry-cell type. One end of said case is closed by a threaded switch plug 4 and the other end by a threaded cable retaining plug 5. Since the case 1 may normally be made from relatively thin material, the threading 20 therein which cooperates with the threading of the closure plugs at each end may advantageously be made by properly indenting the walls of the case as indicated at numerals 6, 7 and 8.

The cable retaining plug is of substantially 30 cylindrical shape having a knurled flange 9 and threading 10. The outer end of said member extends somewhat beyond the flange 9 and is steppedly tapered downwardly to a smaller diameter to provide an attractive finished appearance 35 for this end of the battery case. At the inner end of said member is a somewhat elongated boss 12.

Extending through said member and through 40 said elongated boss is a central opening 13 accommodating the supporting cable 14 and a central electrically conductive wire 15. The cable 14 terminates substantially flush with the end of the boss 12, and the central wire 15 extends on through an insulating washer 16 to a battery contact 17 to which said wire is fastened in any convenient way, as by soldering. This contact is held 45 against the terminal 18 of the battery 2 when the electrical circuit is closed. A coil spring 19 surrounds the boss 12, being held at its one end by the end of the cable retaining plug 5 from which 50 the boss 12 extends and surrounding said boss, and being held at its other end by the end of the battery 2 surrounding the terminal 18.

A tubular cable 14 is woven from a plurality of fine steel wire elements and is of any convenient 55 type which may be placed into a selected position and which when so placed will hold such

position. At least one available cable of this kind provides tubular weaving wherein a plurality of strands cross each other at substantially right angles to each other, one group describing a helix extending in one direction around said cable and the other group woven into the first group and describing a helix extending in the other direction around said cable.

This cable and the wire contained therein may conveniently be affixed to the closure member 5 by swaging at a point near the end of the boss 12, such as the point 20, or in any other convenient manner.

The cable may be of any length desired but a convenient length has been found to be about eight inches which is a length approximately equal to the length of the battery case when two dry cell batteries are used. This will be found long enough to meet most needs without being so long as to be awkward to handle.

At the other end of said cable is the bulb holding member 21. This member is somewhat step-pedally, or otherwise tapered at its cableward end 22 in order both to provide an attractive appearance and to provide a sufficiently thin section at 23 for swaging to the cable. There extends through said member an opening 24 of one diameter for receiving said cable which opening communicates with an opening 25 of larger diameter which is inwardly threaded at 26 for reception of an ordinary threaded base flashlight bulb 27. The cable terminates substantially flush with or slightly short of the point 23 of widening from the narrow opening 24 to the wider opening 25 and the central wire 15 which extends beyond such point is surrounded by an insulating washer 29. Said wire is fastened to a bulb contact 30 which is by said washer 29 entirely insulated from electrical contact with any part of the socket member 21.

The flashlight bulb may be screwed into the large opening 25 on the threads 26 and its terminal 31 will then touch the contact 30.

The electrical circuit which is shown in the drawing as closed, may be considered as beginning with the battery terminal 18 extending through the central wire 15 to the terminal 31 of the bulb 27 and then through said bulb to outer casing, thence through the socket member 21 back through the cable 14 to the closure member 5, through it and the case 1 to the closure member 4 and thence to the opposite terminal of the battery 3. For this purpose to the two batteries can be considered as a single battery.

It will be observed that by using a beam throwing bulb of the type shown in the drawing this flashlight can be made to throw a limited beam without further attachment. However, a round bulb may be utilized in place of the beam throwing bulb shown without changing my invention.

In assembling the device and closing the electrical circuit to effect the position shown in the drawing, the closure member 4 has been screwed inwardly sufficiently to advance the terminal 18 of the battery 2 into contact with the battery contact 17. This effects substantial compression of the spring 19 so that when the closure 4 is partly unscrewed said spring will push said battery back away from the battery contact 17 and thereby break the electric circuit and deenergize the bulb.

Accordingly, I have disclosed a flashlight meeting the objects and purposes above outlined and maintaining throughout a maximum of structural simplicity.

Several variations may be made from the specific structure herein disclosed without departure from the principles of my invention and hence the hereinafter appended claim should be interpreted to cover such variations excepting where the claim by its own terms expressly provides otherwise.

I claim:

A self-contained illuminating device comprising: a metallic, tubular, body member internally threaded on each end; a metallic, externally threaded, one-piece cap engaging the threads at one end of said body member for closing said one end; an elongated, externally threaded, one-piece closure member defining a central opening and having an integral, elongated, annular collar on one of its ends coaxial with said opening, said closure member engaging the threads at the other end of said body member; a cable including a flexible, woven, metallic, external, sheathing, a metallic core, and a flexible electrically nonconductive wrapping between said sheathing and said core whereby said cable may be bent through an arc in any direction and remain in the shape so bent until urged in another direction; one end of said cable received into said central opening in said closure member and extending into said annular collar; said core at said one end of said cable projecting beyond said sheathing, wrapping and annular collar and having an enlarged metallic contact member on said projecting end of said core; an annular spacer of electrically nonconductive material surrounding said core, positioned between said contact and said annular collar and being of external diameter larger than the internal diameter of said annular collar and of internal diameter smaller than the external diameter of said contact member, whereby the said cable is held within said closure member; a one-piece, metallic, slender tubular head anchored to the other end of said cable; said cable received into said head a major portion of the length of said head; the end of said head away from said cable being equipped with internal threads for receiving a prefocused bulb; said core of said cable projecting beyond the end of said sheathing and said wrapping and having a terminal member thereon in position for contact with said bulb; a washer of electrically nonconductive material surrounding said core between said terminal member and the end of said sheathing and wrapping; said body member being adapted for reception therein of a battery unit; a coiled resilient member surrounding said annular collar and seated against said closure member for urging said battery unit against said cap and away from said contact whereby when said cap is fully screwed into said body member said battery unit is urged against said contact to complete an electrical circuit including said bulb.
